UNITED STATES PATENT OFFICE.

JAMES S. PERRY, OF KALAMAZOO, MICHIGAN, ASSIGNOR TO ALBERT M. GATES, OF SAME PLACE.

RAILWAY-CROSSING.

SPECIFICATION forming part of Letters Patent No. 630,519, dated August 8, 1899.

Application filed May 31, 1899. Serial No. 718,922. (No model.)

To all whom it may concern:

Be it known that I, JAMES S. PERRY, a citizen of the United States, residing at the city of Kalamazoo, in the county of Kalamazoo and 5 State of Michigan, have invented certain new and useful Improvements in Railway-Crossings, of which the following is a specification.

This invention relates to improvements in railway-crossings.

10 The object of the invention is to overcome the objections found to the ordinary crossings in that the rails thereof are not continuous, that they are very expensive to manufacture, and they are liable to get out of order, requiring the closest attention to keep the bolts tight owing to the great vibration caused by passing trains.

The objects of this invention are therefore specifically, first, to provide an improved 20 crossing in which the rails shall be continuous for the passing train; second, to provide an improved arrangement for pivoting sections of rails so that they can be easily shifted to make the crossing rails complete for either 25 of the crossing tracks; third, to provide improved means of supporting swinging rails in a railway-crossing to accommodate and form crossings where tracks of the crossing rail-ways approach at any angle, and, fourth, to 30 provide improved means of locking the rails in position in a railway-crossing of the class here indicated.

Further objects will appear in the detailed description to follow.

35 I accomplish these objects of my invention by the devices and means described in this specification.

The invention is clearly defined and pointed out in the claims.

40 A structure embodying my invention is clearly illustrated in the accompanying drawings, forming a part of this specification, in which—

Figure 1 is a plan view of a railway-crossing embodying the features of my invention. 45 Fig. 2 is a sectional view taken on a line corresponding to a line 2 2 of Fig. 1, looking in the direction of the little arrows at the end of the section-line. Fig. 3 is an enlarged de- 50 tail transverse sectional view taken on a line corresponding to lines 3 3 of Figs. 1 and 3.

Fig. 4 is an inverted detail plan view of one of the rail turn-tables on which the sections of rails swing in my improved railway-crossing. Fig. 5 is an enlarged detail sectional view 55 taken on a line corresponding to lines 5 5 of Fig. 2. Fig. 6 is an enlarged detail elevation view of the lever R and its stand and rock-shaft for operating the locking-bolts in my improved railway-crossing. 60

In the drawings similar letters of reference refer to similar parts throughout the several views.

In the drawings, A A represent the fixed rails of the railroad-crossing, which are supported on suitable timbers. These rails extend until they meet and are mitered together on two sides of the crossing diagonally opposite, the rails resting on plates at their ends to support them evenly and securely in position. The remaining rails are cut off at a considerable distance back of the meeting-point, this distance being determined by the length of the swinging rail required to be employed, which of course varies with the angle 70 at which tracks approach each other. On the point, and with the pivotal center exactly at the point where the rails would meet if extended, is supported a swinging rail B, each end of which is exactly equal to the other. 75 Where the tracks cross at right angles, these rails are in length exactly twice the width of the track, measuring from center of rail. They are pivoted at corners diagonally opposite 80 each other and are secured to turn-tables having a pivotal center at the point at which the shortened rails would meet if extended. Suitable stops e are provided for the swinging rails. 85

The turn-table is made in substantially the 90 same manner as the turn-table in my patent application filed May 16, 1899, Serial No. 717,108, for a railway-switch, and I will not repeat its specific construction at this point, as it is unnecessary, further than to state 95 that its halves are extended to receive the pivot or pivot-bolts a at each end. These turn-tables are exactly equal to each other, and the ends are connected with tie-rods E E, secured by the pivotal connections a a. They 100 are easily adjustable by means of suitable turnbuckles, so that the rails can be adjust-

ed exactly parallel to each other somewhat on the principle of parallel-rulers. It will be observed that where the crossing tracks cross at right angles by swinging the rails ninety degrees they will have swung completely from one track into the other, so that the tracks are completely under the control of the attendant at this point.

- I preferably effect the swinging of the rails 10 to operate the crossing by means of a lever F, which is secured to one of the turn-tables, as clearly appears in Figs. 1 and 3 of the drawings. While this lever F might be locked and make a fairly effective crossing, I prefer to 15 provide a lock for the rails at each joint. At the joints farthest from the center I provide pins L, supported on suitable guides secured to the web of the rail, consisting of a folded piece of metal n. I provide a bracket r with 20 a suitable perforation on the end of the swinging rail to receive the locking-bolt on the end of the fixed rail. Where the rails extend to the meeting-point, I provide long bolts K, which extend through perforations in the web 25 of the rail and are also supported by small brackets n, secured to the webs of the rails. Where these bolts K extend through the webs of the crossing rails, they cross each other, one above and one below, and the brackets r 30 on the ends of the swinging rails are located at the right height to receive the points of these locking-bolts, and of course the short bolts are located at the same height on the rails which do not extend to the meeting-point. Extending under the rails of the 35 tracks and through the timbers at a considerable distance back from the crossing-point are rock-shafts G H I J—that is, at a point sufficiently far back from the crossing-points 40 to extend under each of the rails A of each approaching track. Extending up on these rock-shafts are arms M at each end, which are provided with suitable journal-bearings that receive the outturned ends or any suitable pins on the locking-bolts K K K L L 45 L L. A lever R is secured to the rock-shaft G to actuate the same and is provided with a suitable lock-stand R'. On the rock-shaft G is an arm N, extending downwardly, and from 50 this a rod d extends to a bell-crank O, supported on a bracket O' between the rails of the crossing track, and a further rod d' extends on in the same direction as rod d and connects to an upwardly-extending arm N' on 55 shaft I. A rod b connects the bell-crank O and extends therefrom to an upwardly-extending arm P on the rock-shaft H. On the end of the rock-shaft H is a downwardly-extending arm Q. A connecting-rod c extends from this downwardly-extending arm along the rail of its track beneath the rails of the crossing track and connects to the upwardly-extending arm Q' on the rock-shaft J. From these connections it will be observed that when the lever R is raised all of 60 the locking-bolts will be withdrawn. The operator can then shift the crossing by means 65

of the lever F. When he has swung it to the desired position, he can push the locking-lever R down, and the pointed bolts will slide 70 into the eyes provided on the swinging rails and force the swinging rails into correct position and lock them at both ends.

I have described my improved railway-crossing in its most approved form. I believe 75 the improved turn-tables which I have provided are particularly well adapted for use in this connection on account of their great strength and stability and the ease with which they can be operated. It will be noted that 80 heavy plates D with circular heads D' are provided, which are embraced by suitable journaled members C, to which the rails are secured by a modified fish-plate, all of which is specifically described in my former application referred to.

While I have in this connection shown the turn-tables connected together, I wish to remark that the rails themselves might be connected directly by providing them with suitable pivots; but owing to slight inaccuracies in the rails themselves I prefer to connect the turn-tables instead. The particular lock I have shown for the swinging rails in this connection is efficient; but I am aware that 95 other locking means might be provided, as I have already intimated in the description.

Having thus described my invention, what I claim as new, and desire to secure by Letters Patent, is—

1. In a railway-crossing, the combination of a single rail of each approaching track extending to meet the adjacent rail to form an angle at each side of the track diagonally opposite from each other, the remaining rails being cut off at a distance back from the track equal to the distance across the track in the direction in which the rails are extending; swinging rails supported on pivots on points opposite said angles with the central point at the point where the shortened rails would meet if extended; connections between the swinging rails so they will swing parallel to each other; and means of swinging the same, for the purpose specified. 105

2. In a railway-crossing, the combination of a single rail of each approaching track extended to meet the adjacent rail to form an angle at each side of the track diagonally opposite from each other, the remaining rails being cut off at a distance back from the track equal to the distance across the track in the direction in which the rails are extending; swinging rails supported on pivots at points opposite said angles with the central point at 110 the point where the shortened rails would meet if extended; connections between the swinging rails so they will swing parallel to each other; means to swing the same; and means of locking the swinging rails in line 115 with the fixed rails; rock-shafts under each of the approaching tracks at a point beneath the fixed rails thereof; upwardly-extending arms on said rock-shafts; locking-bolts in 120

125

130

suitable guides on the fixed rails; brackets with suitable eyes on the ends of the swinging rails to receive the ends of said locking bolts; connections between the said rock-shafts and a lever to actuate the same to throw the locking-bolts into or out of engagement, for the purpose specified.

3. In a railway-crossing, the combination of a single rail of each approaching track extended to meet the adjacent rail to form an angle at each side of the track diagonally opposite from each other, the remaining rails being cut off at a distance back from the track equal to the distance across the track in the direction in which the rails are extending; swinging rails supported on pivots at points opposite said angles with the central point at a point where the shortened rails would meet if they were extended, these said pivots consisting of base-plates D, having circular heads D', thereon; and members C, C, containing journal-bearings bolted to the side thereof

and secured to said swinging rails; and means of coupling said swinging rails together so that they will swing parallel from one track 25 to the other, for the purpose specified.

4. In a railway-crossing, the combination with the rails of the meeting tracks of the swinging rails pivoted at opposite diagonal meeting-points of the fixed rails and extending in both directions from the pivotal center distances not less than the width of the track; and means of swinging said rails so that they will shift from one track to the other, the fixed rails of both tracks being set back to 35 receive the swinging rails, for the purpose specified.

In witness whereof I have hereunto set my hand and seal in the presence of two witnesses.
